UNITED STATES PATENT OFFICE.

CESARE BARBIERI AND PAUL CARPENTER, OF CHICAGO, ILLINOIS.

MACHINE FOR TREATING PHOTOGRAPHIC PRINTS WITH FLUIDS.

1,292,230.

Specification of Letters Patent. Patented Jan. 21, 1919.

Application filed December 16, 1911, Serial No. 666,227. Renewed June 3, 1918. Serial No. 238,034.

To all whom it may concern:

Be it known that we, CESARE BARBIERI and PAUL CARPENTER, respectively a subject of the King of Italy and a citizen of the 5 United States, and both residents of Chicago, in the county of Cook and State of Illinois, have invented certain new and useful Improvements in Machines for Treating Photographic Prints with Fluids, of which 10 the following is a specification.

Our present invention relates in general to machines for treating with fluids photographic prints which require treatment by fluids subsequent to exposure to light, and 15 has special reference to the construction of an improved type of so-called "continuous machine" adapted for treating and washing the prints either subsequently or independently of printing them.

20 The principal objects of our present invention are the provision of an improved arrangement of softening bath, treating bath and clarifying bath; the provision of a machine wherein the exposed surface of 25 the prints may be so treated with fluids or washed as to avoid unnecessary saturation of the paper and insure contact of the minimum effective amount of fluid therewith; the provision in a print washing machine of 30 means for washing the under side of the printed surface; the provision of improved means for removing excess moisture from the washed prints; the provision of an improved arrangement of wringer device for 35 such purpose; and generally to improve, cheapen and simplify the construction of machines for treating and washing photographic prints subsequent to their exposure to light embodying one or more of the several steps referred to, together with such 40 further objects as will hereinafter appear.

Machines available at this day for certain of the purposes referred to, as known to us, are objectionable in that they lack 45 adequate means for washing such prints (even were they otherwise satisfactory) with sufficient rapidity, and lack effective means for drying the prints after washing; and the prints made by such machines are generally delivered in a crinkled condition. 50 Such machines also have further disadvantages suggested by the above stated objects and known to those who are skilled in the art to which our invention pertains.

55 In overcoming certain disadvantages referred to and in attaining the foregoing ob-

jects and certain additional benefits and advantages to be below disclosed we have provided the construction illustrated in the accompanying drawings, wherein—a side elevational view is shown, partly in section, with certain parts removed for the sake of clarity, illustrating a preferred form of machine embodying our invention.

On inspection of the drawings it will be observed that we have shown only that part of a machine for making photographic prints which relates to the treatment of such prints with fluids after they have been exposed to the action of light.

The apparatus is conveniently supported by parallel frame members 10, 11 suitably spaced apart, the said frame members and the mounting for the parts being substantially duplicated for both sides of the machine.

The printed paper as it leaves the photo-printing apparatus is caused to pass under the roll 60 during its progress toward the rear of the machine, during which time the 80 printed sensitized surface of the paper is downwardly disposed. To the end that a minimum amount of fluid be absorbed by the paper, and dissipation of fluid, stretching of the paper and loss of time in drying with consequent increase of expense and lowering of volume of production, be avoided, we prefer to treat the under surface only of the paper. This mode of procedure enables us to prevent an accumulated water bath on the paper with consequent saturation thereof and saves the expense of complicated stretching devices, not to mention other obvious advantages.

In order that this printed surface may now be subjected to treatment by the required fluid for treating the print, we employ one or more, as may be required, of a series of treating devices, which we will now describe in connection with a preferred 100 form of apparatus for fixing blue-prints, viz.:

In carrying out the stated procedure we pass the printed paper as it leaves the roll 60 over a series of rolls here including a roll 105 61, a series of rolls 62, 63, 64 and a roll 65, all of which are desirably provided with a rubber surface not alone to resist the action of the water or other fluid but also to prevent relative slippage between them and the paper. Of these rolls 65 is the only one positively driven, the others being rotated

by the movement of the paper itself. The roll 65 is driven from the motor 140 by means of the worm 152, worm wheel 153, sprocket 153^a, chain 23, sprocket 33, bevel gears 160 and 161, shaft 162 and bevel gears 161^a and 160^a.

- At some convenient point between the rolls 60 and 61 we arrange a connection 66 to a source of treating fluid, and provide a 10 splash-plate 67 coöperating therewith, whereby the printed surface is given its initial wash. To catch any fluid which may perchance drip from the sheet 31 a drip tank 68 having, if desired, discharge through a 15 drain pipe 69 is mounted immediately below the roll 60 whose periphery should be below the periphery of the roll 34 in order to insure that any drippage there may be will fall into the tank 68.
- 20 Where a second fluid treatment is desirable, a similar combination of a source of fluid 70 provided with a coöperating splash-plate 71 and drip-tank 72 provided with a strainer 72^a is arranged to care for the flight 25 between the rolls 61 and 62, and where a third fluid treatment is desirable a like arrangement embodying similar elements, indicated at 73, 74, 75, is employed to act on the run between the rolls 64 and 65.
- 30 In order to avoid scraping and hence marring the surface of the paper 31, the splash-plates are preferably arranged so as not to contact therewith but to be closely adjacent the planes of travel thereof.
- 35 In the manufacture of blue prints, the connections 66 and 73 would be supplied by water from the inlet pipe 76, for softening and washing-off and clarifying the printed surface, respectively, and the drain pipe 69 40 would discharge into the sewerage system, but the connection 70 would be supplied with a solution of potash for fixing the prints which solution could be used repeatedly. We therefore arrange in circuit between the connection 70 and the drip tank 45 72 a suitable pump 77 communicating therewith by means of pipes 78 and 79.

For a three fold purpose, first: to prevent mixture of the potash solution and the wash-off water and consequent dilution and weakening of such solution; second: to remove any excess potash solution and moisture remaining on the surface of the paper; and, third: to tension the paper and compensate 50 for any tendency toward stretching thereof, we interpose between the rolls 62 and 64, which are preferably rotatably mounted with their axes fixed against vertical movement relatively to the frame, a third roll 63, 55 over which the paper passes. The last mentioned roll has a floating axis by virtue of the fact that it is carried in journals movable vertically in slots 77^a provided in the frame, and that such journals are yieldingly 60 resistantly supported by springs 78 one not

shown against the tendency of the paper to depress the roll.

Since the rolls 62, 63, 64 rotate in the directions indicated by the arrows the rear margin of the tank 72 should be arranged behind the axis of the roll 63 in order to catch any drippings therefrom consequent upon the pressure exerted upon the sheet passing between the rolls 62 and 63. 70

From the foregoing description it will be 75 manifest that by the use of our improved arrangement of the paper in angularly disposed runs, we are enabled to subject it to a plurality of treatments by fluid without increasing the height of the machine, thereby 80 requiring a large amount of head-room and that devices for additional fluid treatments may readily be added without materially adding to the length of the machine with consequent increase in the floor space 85 required for its installation.

The paper after leaving the roll 64 passes 90 upward to the rolls 80, 65 and 90 of a drying apparatus described in a co-pending application.

For actuating the several parts of the machine, we have above described, we provide suitable driving mechanism preferably employing therein as here shown an electric motor 140 having suitable connections 95 as indicated at 141, 142, to a source of current supply (not shown). On the motor shaft 143 we provide a pinion 144 driving a gear 145 on a shaft 146 having a sprocket 147 by means of which the pump 77 is driven 100 through a chain 148 and pinion 149. Moreover, since the pump 77 as well as the several rolls are all driven by the same motor, the operation of the device is greatly simplified. Furthermore inasmuch as the bearings of 105 the members 34, 146, 60, 61, 62, 63, 64, 80 and 65 are in alinement, it is apparent that in the construction of a machine embodying our improvements we have provided as far as may be against distortion of the paper in 110 its passage therethrough.

In view of the foregoing specification, it is thought that a more amplified description of the operation of the machine will be unnecessary and that it will be readily understood by those who are skilled in the art to which our invention pertains. 115

Having thus described our invention and illustrated its use, what we claim as new and desire to secure by Letters Patent is:

1. An apparatus of the character described comprising, in combination, means for producing a stream of fluid, means for treating therewith one surface of a print produced photographically, and means for removing excess fluid from the treated surface while moving in an upward direction after it leaves said treating stream. 125

2. An apparatus of the character described comprising, in combination means 130

- for producing a stream of fluid, means for treating therewith one surface only of a print produced photographically, and means for squeezing excess fluid from the print 5 while moving in an upward direction.
3. An apparatus of the character described comprising, in combination, means for producing a stream of fluid, means for treating therewith one surface only of a print produced photographically, and a pair of pressure rolls for removing excess fluid from the print while moving in an upward direction.
- 10 4. An apparatus for treating a sheet of paper with a plurality of fluids comprising, in combination, a plurality of oppositely disposed sheet guiding devices whereby the sheet may be guided in a plurality of runs, and a plurality of fluid supply means whereby different fluids may be applied successively to the under surfaces of said several runs of the sheet.
- 15 5. An apparatus for treating a sheet of paper with a plurality of fluids comprising, in combination, a plurality of oppositely disposed sheet guiding devices whereby the sheet may be guided in a plurality of runs, a plurality of fluid supply means whereby different fluids may be applied successively to the under surfaces of said several runs of the sheet, and means interposed between said several fluid supplies whereby excess fluid may be removed from one of said runs of the sheet before fluid is applied to the 20 sheet in another run thereof.
- 25 6. An apparatus for treating a sheet of paper with a plurality of fluids comprising, in combination, a plurality of oppositely disposed sheet guiding devices whereby the sheet may be guided in a plurality of runs, and a plurality of fluid supply means whereby different fluids may be applied successively to the under surfaces of said several runs of the sheet, one of said guiding devices being arranged for the removal of excess fluid applied to one of said runs from one of said fluid supplies before said run is exposed to fluid from another of said fluid supplies.
- 30 7. In an apparatus for treating a sheet of paper with a plurality of fluids, a plurality of upper sheet guiding devices and a plurality of lower sheet guiding devices arranged to guide a sheet in a plurality of runs arranged at an angle to each other, a plurality of means for applying fluids to the under sides of said several runs in succession, and catch basins below said fluid supplies for receiving the excess of the fluids applied 35 to said runs.
- 35 8. In an apparatus for treating a sheet of paper with a plurality of fluids, a plurality of upper sheet guiding devices and a plurality of lower sheet guiding devices arranged to guide a sheet in a plurality of runs 40 arranged at an angle to each other, a plurality of means for supplying fluids to the under sides of said several runs in succession, and catch basins below said fluid supplies for receiving the excess of the fluids applied to said runs, said lower sheet guiding devices being arranged to discharge excess fluids from said runs into said catch basins. 70
9. An apparatus of the character described comprising, in combination, a plurality of sources of fluid for treating a print produced photographically, and variable tensioning means interposed between said sources of fluid and adapted to act upon the print whereby warping of the print is restrained. 75
10. An apparatus of the character described comprising, in combination, a plurality of sources of fluid for treating a print produced photographically, one thereof being adapted to direct fluid to the bottom surface of the print only, a receiver for fluid from said last mentioned source, and a plurality of rolls interposed between said sources of fluid and adapted to act upon the print to remove excess liquid therefrom and direct it into said receiver, for preventing mixture of the fluids. 80
11. An apparatus of the character described comprising, in combination, a plurality of sources of fluid for treating a print produced photographically, and three rolls interposed between said sources of fluid and adapted to act upon the print, two of said 90 rolls being arranged for restraining the mixture of said fluids, and the third being arranged for tensioning the print. 95
12. An apparatus of the character described comprising, in combination, a plurality of sources of fluid for treating a print produced photographically, and three rolls interposed between said sources of fluid and adapted to act upon the print, two of said rolls being arranged for restraining the mixture of said fluids, and the third being arranged for removing fluid from the print. 105
13. An apparatus of the character described comprising, in combination, a plurality of sources of fluid for treating a print produced photographically, and three rolls interposed between said sources of fluid and adapted to act upon the print, two of said rolls being arranged for restraining the mixture of said fluids, and the third bearing on the other two and being arranged for tensioning the print and removing fluid therefrom. 110
14. An apparatus of the character described, comprising, in combination, a source of treating fluid, a paper supply, means for moving the paper past the source of fluid, means for directing a stream of fluid to the bottom surface only of the paper and means for removing excess fluid therefrom while 130

moving in an upward direction whereby the accumulation of fluid thereon is normally prevented.

15. An apparatus of the character described comprising, in combination, a plurality of sources of fluid, a paper supply, means for moving the paper past the sources of fluid, and means for directing separate streams of fluid from said sources to the bottom surface of the paper while moving substantially vertically whereby the accumulation of fluid thereon is normally prevented.

16. An apparatus of the character described comprising, in combination, a plurality of sources of fluid, a paper supply, means for moving the paper past the source of fluid, and means for directing separate streams of fluid from said sources to different portions of the bottom surface of the paper while moving substantially vertically whereby the accumulation of fluid thereon is normally prevented.

17. An apparatus of the character described, comprising, in combination, a plurality of sources of fluid, a paper supply, means for moving the paper past the sources of fluid, means for successively deflecting the paper into different substantially vertical

planes, and means for directing separate fluid supplies from said sources to portions of the bottom surface of the paper in such substantially vertical planes whereby the accumulation of fluid thereon is normally prevented.

18. An apparatus of the character described comprising, in combination, a source of water supply, a source of treating fluid supply, a supply of photographically printed paper, means for moving the paper past the said sources of fluid, and means for directing first water, then treating fluid, and finally water again to the under surface of the paper, whereby said paper surface is first softened by said water, the print thereupon then fixed by said treating fluid, and the excess treating fluid finally removed by water and the print clarified without accumulation of fluid on said paper.

In testimony whereof we have hereunto signed our names in the presence of the two subscribed witnesses.

CESARE BARBIERI.
PAUL CARPENTER.
